Fig. 1 is a front elevational view of a drive-in restaurant showing my new design.

Fig. 2 is a rear elevational view with the upper portion broken away for convenience of illustration.

Fig. 3 is a top plan view on a somewhat reduced scale.

Fig. 4 is a side elevational view with the upper portion broken away for convenience of illustration.

Fig. 5 is also a side elevational view opposite that shown in Fig. 4.

Fig. 6 is a horizontal sectional view (taken on line 6-6 of Fig. 4).

I claim:

The ornamental design for a drive-in restaurant, as shown and described.
